UNITED STATES PATENT OFFICE.

WILLIAM H. PERRY, OF CONCORD, NEW HAMPSHIRE.

DESIGN FOR A MONUMENT.

SPECIFICATION forming part of Design No. 23,958, dated January 22, 1895.

Application filed December 20, 1894. Serial No. 532,501. Term of patent 7 years.

To all whom it may concern:

Be it known that I, WILLIAM H. PERRY, a citizen of the United States, residing at Concord, in the county of Merrimac and State of New Hampshire, have invented and produced a new and original Design for a Monument, of which the following is a specification, reference being had to the accompanying drawing.

The leading feature of my design lies in the configuration of the shaft, its ornamental top or cap piece, and in the various ornamental tablets, and character of the surfaces of the different parts, all of which will be fully set forth in the following specification and claim, and clearly illustrated in the accompanying drawing forming a part of same, reference being had to the drawing by figures and letters, as follows:

The base 1, has four vertical sides which terminate in an obtuse frustum of a pyramid 2, upon which rests the pedestal 3, terminating at its top in an acute frustum of a pyramid 4, upon one or more sides of which may be placed a raised tablet 5, as shown. The sides of said pedestal are vertical, as are also those of the base, but the shaft has slightly tapering sides 6, upon which are the raised tablets 7 and 8 and the tablets 9, the latter being distinguishable by a heavy border line substantially of the configuration shown at 10. The tablets 7, are located at the bottom of the shaft, their upper edge describing an arch 11, of central location with small semi-arches 12, at each end or corner,

and short horizontal portions 13, connecting the said arches, the upper edge of said tablets 7, being beveled as shown at 14. Of the tablets 8, the lower edges are beveled as at 15, and take the form of an arch 16, having dove-tailed notches as seen at 17, the center of one or more of these tablets 8, being ornamented by an urn 18, shown in relief and having a plant in blossom. The upper edge of said tablet 8, having the urn upon it will be arched as at 19, just above said urn, and the corners of said tablets are chamfered as at 20. The tablets 8, terminate in an obtuse frustum of a pyramid 21, ornamented with the raised tablet 22, upon which rests the ornamental cap piece 23, the larger portion of which is represented by vertical octagonal sides 24, the lower portions of which incline inward and downward meeting the tablets 22 at 25, the said cap-piece terminating at its top in an eight sided pyramid 26.

55

The ornamentation of my design by surfaces of different character is designated by the letters A, B, C; A, representing rockwork; B, hammered work, and C, polished work.

What I claim as my invention is—

60

The design for a monument substantially as described and set forth.

In testimony whereof I affix my signature in presence of two witnesses.

WILLIAM H. PERRY.
